UNITED STATES PATENT OFFICE.

HYMAN BOLOTIN, OF CHICAGO, ILLINOIS.

DESIGN FOR A WEDDING RING.

Application filed February 15, 1928. Serial No. 25,447. Term of patent 7 years.

To all whom it may concern:

Be it known that I, HYMAN BOLOTIN, a citizen of the United States, residing at Chicago, in the county of Cook and State of Illinois, have invented a new, original, and ornamental Design for a Wedding Ring, of which the following is a specification, reference being had to the accompanying drawings, forming part thereof.

Fig. 1 is an end view of a wedding ring, showing my new design.

Fig. 2 is a side elevation of the same.

Fig. 3 is an enlarged radial section of the same ring, taken along the line 3—3 of Fig. 1.

I claim:

The ornamental design for a wedding ring as shown.

HYMAN BOLOTIN.
